UNITED STATES PATENT OFFICE

142,286

DESIGN FOR A REFUSE BAG HOLDER

John L. Mayer, Kansas City, Mo.

Application April 16, 1945, Serial No. 119,013

Term of patent 3½ years

(Cl. D44—1)

To all whom it may concern:

Be it known that I, John L. Mayer, a citizen of the United States, residing at Kansas City, in the county of Jackson and State of Missouri, have invented a new, original, and ornamental Design for a Refuse Bag Holder, of which the following is a specification, reference being had to the accompanying drawing, forming a part thereof.

Fig. 1 is a front perspective view of the refuse bag holder, in an open position, showing my new design; and

Fig. 2 is a back perspective view thereof, in the closed position.

I claim:

The ornamental design for a refuse bag holder, as shown.

JOHN L. MAYER.
